Inventor:
Joseph Adrian Thebault

UNITED STATES PATENT OFFICE

104,122

DESIGN FOR AN EMBLEM

Joseph Adrian Thebault, Raleigh, N. C.

Application September 30, 1936, Serial No. 65,076

Term of patent 14 years

To all whom it may concern:

Be it known that I, Joseph Adrian Thebault, a citizen of the United States, residing at Raleigh, in the county of Wake, State of North Carolina, have invented a new, original, and ornamental Design for an Emblem, of which the following is a specification, reference being had to the accompanying drawing, forming a part thereof.

Fig. 1 is a front elevational view of the emblem showing my new design.

Fig. 2 is an edge view thereof.

I claim:

The ornamental design for an emblem, as shown.

JOSEPH ADRIAN THEBAULT.
